UNITED STATES PATENT OFFICE.

JAMES J. GIBNEY, OF MINNEAPOLIS, MINNESOTA, ASSIGNEE, BY MESNE ASSIGNMENTS, TO UNIVERSAL PRODUCTS CORPORATION, OF MINNEAPOLIS, MINNESOTA, A CORPORATION OF MINNESOTA.

HUMIDIFIER.

Application filed October 24, 1927. Serial No. 228,254.

My present invention has for its object the provision of a highly efficient humidifier intended for general use but especially well adapted for a cigar case. Said invention further provides a simple and highly efficient hygrometer of novel construction for automatically controlling the humidifier.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view of the humidifier and hygrometer principally in central vertical section;

20 Fig. 2 is a view partly in plan and partly in horizontal section taken on the line 2—2 of Fig. 1;

Fig. 3 is a view principally in horizontal section taken on the line 3—3 of Fig. 1;

25 Fig. 4 is a bottom plan view of the base and hygrometer; and

30 Fig. 5 is a view corresponding to Fig. 1 on a much reduced scale with some parts removed and further illustrating the electric wiring for the apparatus.

The humidifier, as illustrated, includes a bowl-like casing 6 mounted on a base 7 in the form of an inverted bowl having a plurality of circumferentially spaced air intake ports 8 formed therein near the lower edge thereof. The casing 6 is provided with a cover 9 held thereon by a capping flange 10. Formed in the cover 9 is a plurality of circumferentially spaced apertures 11 for the display of advertising matter or other indicia between a pair of transparent or translucent plates 12.

35 The casing 6, near its top, is provided with an annular internal supporting shoulder 13. A multiplicity of air escape passages 14 are formed in the casing 6 between its shoulder 13 and the top of said casing.

40 Removably mounted in the casing 6 is a reservoir 15 of substantially the same shape as the casing 6. This reservoir 15 is provided with an external annular shoulder 16 which rests on the shoulder 13 and removably supports said reservoir in the casing 6. In the upper edge portion of the reservoir

15 is a multiplicity of notch-like air escape 55 passages 17 that are normally coincident with the air escape passages 14. By turning the reservoir 15 in the casing 6, the air escape passages 17 may be circumferentially offset in respect to the air escape passages 14 60 to reduce the conducting capacity of the air escape passages 14.

The bottom of the reservoir 15 is spaced materially above the bottom of the casing 6 and at the axis thereof is an upstanding 65 flue, comprising a lower section 18 and a relatively movable upper section 19, that affords an air intake passage 20. The lower flue section 18 is integrally formed with the bottom of the reservoir 15 and extends above 70 the level of a body of water α in said reservoir. The upper flue section 19 is entirely above the body of water α and normally rests on the upper edge of the lower flue section 18.

75 Surrounding the flue 18—19 is a wick comprising a lower section 21 and an upper section 22 applied, respectively, to the lower flue section 18 and upper flue section 19. Normally the wick sections 21 and 22 have 80 contacting engagement at their abutting edges so that capillary attraction will convey the water α to the upper wick section 22 through the lower wick section 21, which, as shown, is entirely submerged in the body of 85 water α except its upper edge portion.

The reservoir 15 is provided with a dish-like cover 23 that is removably supported on the shoulder 16 and has an axial opening through which the upper flue section 19 and 90 the upper wick section 22 extends with freedom for vertical movement. This cover 23 causes all moisture in the reservoir 15 to pass through the upper wick section 22 in the escape passage through the ports 17 95 and 14. On the marginal edge of the cover 23 is a damper 24 in the form of an upstanding annular flange that snugly fits within the expanded upper end portion of the reservoir 15 and is normally below the air escape passages 17. By raising the cover 23 its damper 24 will partly or entirely close the air escape passages 17 to vary the air conducting capacity thereof.

100 A multiplicity of coincident circumferentially spaced air ports 25 are formed in the bottom of the casing 6 and the top of the base 7 for the passage of air entering said

base through the ports 8 into the casing 6. From the bottom of the casing 6 the air travels upward through the air passage 20 and into the top of said casing above the cover 23 where the same escapes through the air passages 14 and 17.

Rigidly secured to the bottom of the casing 6 in axial alignment with the flue 18-19 is an electric light socket 26 having mounted therein a light bulb 27 and which socket is of the type to cause the light bulb 27 to flicker. The feed wires 28 for the socket 26 enter the base 7 through an insulating bushing 29.

15 Connections including a hygrometer in the base 7 are provided for automatically raising and lowering the flue section 19 and the attached wick section 22 to break and make the contact between the wick sections 20 21 and 22. This hygrometer is of a novel construction and, as shown, includes a hydro-responsive member 30 formed from a fibrous material preferably a piece of mahogany cut crosswise of the grain. One 25 end of the member 30 is mounted in and secured by a pivot to an anchor bracket 31 rigidly secured to the base 7, at the top thereof. The other end of the member 30 has a clip 32 attached thereto and which 30 clip is provided with a stem 33 pivoted to the short upturned end of an L-shaped lever 34 intermediately fulcrumed to a bracket 35 rigidly secured to the base 7 at the top thereof. The long or free arm of the lever 34 extends longitudinally of and below the 35 member 30.

The connections heretofore referred to for raising and lowering the flue section 19 and wick section 22 include also a vertical 40 plunger 36 having a head at each end and slidably mounted in a sleeve bearing 37 in the bottom of the casing 6 and top of the base 7. Loosely telescoped into the flue 18-19 from the bottom of the reservoir 15 45 is a sleeve 38 having on its lower end an outturned annular flange 39 which rests on the headed upper end of the plunger 36. The lever 34 is provided with an abutment 40 arranged to engage the headed lower 50 end of the plunger 36 and operate the same.

A plurality of shouldered thumb screws 41 extend through vertical slots 42 in the upper wick section 22 and vertical slots 43 in the upper flue section 19 and have threaded engagement with the sleeve 38.

By tightening the thumb screws 41 the sleeve 38 and upper flue section 22 may be rigidly connected for common vertical movement and by loosening said screws, the 60 upper flue section 19 will remain idle during the raising and lowering of the sleeve 38.

Notch-like passages 44 are formed in the cover 23 for the screws 41 during the raising and lowering of the upper flue section

19 and wick section 22. By slightly rotating the upper flue section 19 and the connected sleeve 38 relative to the cover 23, the heads of the screws 41 may be moved out of registration with the passages 44 and positioned under the cover 23 so that said cover will be raised and lowered with the upper flue section 19 and wick section 22 and thereby operate the damper 24 for opening and closing the air escape passages 17. By 75 lifting the upper flue section 19 and wick section 22 to carry the screws 41 through the notches 44 and then turning said sections 19 and 22 to carry the screws 41 out of registration with the passages 44, the 80 upper flue section 19, wick section 22 and connected sleeve 38 may be supported from the cover 23 with said wick section to break the contact between the wick sections 21 and 22 and thereby render the humidifying device 85 inoperative.

A circuit breaker operated by the hygrometer is interposed in the circuit for the light bulb socket 28. This circuit breaker includes a relatively fixed adjustable contact screw 45 carried by the bracket 31 and a co-operating relatively movable contact screw 46 carried by the long arm of the lever 34. A wire 47 connects the contact screw 45 to a switch 48 in the light bulb socket 95 28 and a wire 49 connects the contact screw 46 to said switch. In one position of the switch 48 the light circuit 28 is shunted around the circuit breaker and in the other position of said switch said light circuit is 100 completed through the circuit breaker and at which time the contact screw 46 is held in contact with the screw 45 by the hygrometer.

Referring again to the hygrometer I have 105 found that a very sensitive and highly efficient hydro-responsive element for various different uses may be obtained by cutting a piece of wood crosswise of the grain. As is well known, the expansion and contraction 110 of a piece of wood crosswise of the grain is much greater than that lengthwise thereof. Wood, such as mahogany, is very sensitive to moisture and when dry absorbs moisture very quickly and when filled with 115 moisture will give the same off very readily in a dry atmosphere.

The hydro-responsive element 30, as illustrated, is arranged to operate a movable element by endwise expansion or contraction 120 depending on the amount of humidity in the air. In some instances it might be desirable to anchor both ends of the hydro-responsive element 30 and cause the same to operate a movable element by a lateral 125 movement. In this use of the element 30 the same will be straight when dry and bowed laterally when filled with moisture.

As illustrated in the drawings, the hydro-responsive element 30 is holding the circuit 130

breaker open so that the circuit to the electric light bulb 27 is broken and hence the artificial means, to wit: said light bulb inactive for producing artificial evaporation of the water in the reservoir 15. In this position of the circuit breaker a proper amount of humidity is obtained by the natural evaporation of the water α through the wick sections 21 and 22. In case there is sufficient 10 humidity in the air, to cause a further extension of the hydro-responsive element 30 over that shown in the drawings, the abutment 40 on the lever 34 will engage and lift the plunger 36 and thereby lift the sleeve 38, flue 15 extension 19 and wick section 22. This lifting of the wick section 22 breaks its contact with the wick section 21 and prevents further evaporation of the water α through the wick sections 21 and 22.

20 When the humidity is less than that required, the hydro-responsive element 30 will be contracted and lower the wick section 22 in case the same is being held out of contact with the wick section 21 and further contraction of said element will carry the contact screw 46 into engagement with the contact screw 45 and thereby complete the circuit for the light bulb 27 to artificially start evaporation of the water α by the heat from 30 said lamp. In case the contact between the wick sections 21 and 22 is broken and still there is too much moisture in the atmosphere, the switch 41 may be manually operated to shunt the circuit-breaker 45—46 and 35 thereby complete the circuit to the lamp bulb 27 so that the heat from said bulb will dry out the air.

The air conductive capacity of the air escape passage 14 may be varied, at will, as 40 previously stated, by manually turning the reservoir 15 in respect to the casing 6 to offset the air escape passages 17 in respect to the air escape passages 14. Or by rotating the cover 23 sufficiently to carry the passages 45 44 out of alignment with the screws 41, said cover will be automatically raised and lowered with the wick section 22 to close and open the ports 17 and hence the ports 14.

What I claim is:

50 1. A humidifier comprising a reservoir containing a body of water, a wick comprising contacting lower and upper sections, the former of which is in the body of water and the latter of which is above the same, and

operating connections for the upper wick 55 section including a hydro-responsive controlling element for making and breaking the contact between the wick section.

2. The structure defined in claim 1 in further combination with a heating element 60 closely associated with the wick sections.

3. A humidifier comprising a reservoir containing a body of water, said reservoir having a flue affording an air passage and comprising a lower section and a relatively 65 movable upper section, said lower flue section being in the body of water and extending above the same and said upper flue section being above the body of water, a wick comprising lower and upper contacting sections applied respectively to the lower and upper flue sections, and operating connections 70 for the upper flue section including a hydro-responsive controlling element for making and breaking the contact between 75 the wick sections.

4. The structure defined in claim 3 in further combination with a heating element in the flue, and manually-operated means in said connections for holding the upper flue 80 section raised to break the contact between the wick sections.

5. A humidifier comprising a reservoir for holding a body of liquid, and a wick comprising lower and upper sections the former 85. of which is arranged to project into the body of liquid and above the same, one of said sections being movable in respect to the other to make and break the contact between said sections.

6. The structure defined in claim 5 in further combination with manually controlled means for holding the movable wick section out of contact with the other wick section.

7. A humidifier comprising a reservoir for holding a body of liquid, a wick comprising lower and upper sections the former of which is arranged to project into the body of liquid and above the same, one of said sections being movable in respect to the other, 100 and automatic means for operating the movable wick section to make and break the contact between the two wick sections.

8. The structure defined in claim 5 in further combination with a heating element 105 closely associated with the wick sections.

In testimony whereof I affix my signature.
JAMES J. GIBNEY.
